CLAIM

The ornamental design for a rear wheel assembly for a motorcycle to tricycle conversion kit, as shown and described.

DESCRIPTION

FIG. 1 is perspective view;

FIG. 2 is a right side elevation view, the left side elevation view being a mirror image thereof;

FIG. 3 is a top plan view;

FIG. 4 is a front elevation view; and,

FIG. 5 is a rear elevation view.

The broken line showing of a vehicle with tires is for illustrative purposes only and forms no part of the claimed design.
